UNITED STATES PATENT OFFICE.

CARL HITZL, OF CHICAGO, ILLINOIS.

DESIGN FOR A BOTTLE.

SPECIFICATION forming part of Design No. 36,431, dated July 14, 1903.

Application filed June 15, 1903. Serial No. 161,631. Term of patent 14 years.

To all whom it may concern:

Be it known that I, CARL HITZL, a citizen of the United States, residing at Chicago, in the county of Cook and State of Illinois, have

5 invented a new, original, and ornamental Design for a Bottle, of which the following is a specification, reference being had to the accompanying drawings, forming a part hereof.

10 Figure 1 is a view in elevation of a bottle, showing my new design; and Fig. 2, a plan view of the same.

What I claim as new, and desire to secure by Letters Patent, is—

The ornamental design for a bottle, as herein shown.

CARL HITZL.
